UNITED STATES PATENT OFFICE.

PAUL BERGEN, OF RICHWOOD, WISCONSIN.

LIFE-BELT.

1,284,220.

Specification of Letters Patent. Patented Nov. 12, 1918.

Application filed May 2, 1918. Serial No. 232,109.

To all whom it may concern:

Be it known that I, PAUL BERGEN, a citizen of the United States, and a resident of Richwood, in the county of Dodge and State 5 of Wisconsin, have invented a new and Improved Life-Belt, of which the following is a description.

My invention relates to a life-saving appliance including an inflatable life belt and 10 a gas generator adapted to be held on the body of the wearer of the belt and connected to the latter, the generator being adapted to contain a substance which in the presence of water will generate a gas for 15 inflating the belt.

The invention in addition to comprising the main elements of the inflatable belt and connected generator is characterized also by 20 various distinctive features having in view the maximum floatability in the inflated belt and means controlling the admission of water to the gas-producing material.

Reference is to be had to the accompanying drawings forming a part of this specification, it being understood that the drawings are merely illustrative of one example 25 of the invention.

Figure 1 is a side elevation of a life belt and generator embodying my invention;

30 Fig. 2 is an enlarged longitudinal vertical section of the generator;

Fig. 3 is a sectional plan view on the line 3—3, Fig. 2;

Fig. 4 is a transverse vertical section on 35 the line 4—4, Fig. 2;

Fig. 5 is a fragmentary sectional plan view illustrating a slightly modified valve arrangement controlling the admission of water;

40 Fig. 6 is a detail in section on the curved line 6—6 Fig. 3.

A practical embodiment of my invention includes a tubular belt 10, the ends of which are adjustable by a suitable buckle arrangement 45 as indicated by 11, and said belt has suspended thereon, communicating with the interior of the belt, inflatable sacks 12. The belt connects by a section of hose 13, or the like, with a gas generator 14 preferably 50 through the cover 15 thereof. In the illustrated example the hose 13 connects with a nipple 16 on a screw cap 17 threaded onto a neck 18 in the cover 15. The generator

14 is connected with the belt by straps indicated at 19, Fig. 1, secured to the belt at 10^a 55 and secured to lugs 20 or equivalent members on the generator. Also, to prevent the generator from being inverted additional straps may be employed to secure the generator at the bottom to the apparel of the 60 wearer of the belt, there being indicated at 21 a fragment of one of such additional straps. The cover 15 may be removably secured in any suitable manner, there being indicated swing bolts 22 on the generator 65 adapted to be swung into engagement with the cover, the bolts having suitable clamp nuts 23.

The generator includes a gas chamber 24 and a larger water chamber 25, the latter 70 being divided to produce an auxiliary water chamber 26 at the top. In the gas chamber a holder 27 is provided for receiving material adapted in the presence of water to generate gas. The holder 27 in the illustrated form is cup-shaped to receive a cartridge 28 of gas-generating material as, for example, a material known as oxone adapted in the presence of water to generate oxygen gas. Resilient retaining fingers 29 are provided within the holder 27 to retain the cartridge 28. Said holder is shown as having a threaded stem 30 rising from the bottom of the chamber 24, the cup having suitable means for turning it, such as lateral studs 75 31 adapted to receive a suitable wrench. The cap is closed by a soluble disk 32 which is clamped in place by a ring 34 in threaded engagement with the top of the cup 27, the ring having suitable members 34 thereon 80 for turning it.

Water may enter the upper water chamber 26 through an inlet opening 35 and pass from said chamber to the main water chamber 25 through an opening 36 in a horizontal partition 40, separating the chambers 25, 26. The opening 36 is of key-hole shape having an enlarged circular end and an arcuate slot 37 extending therefrom. The opening is closed by a valve 38, which, as 95 shown in Figs. 2 and 6, consists of upper and lower plates disposed respectively above and below the partition 40, said valve being pivoted at one end to the partition 40 by a rivet 39 or the like, there being a second 100 rivet 41 passing through the upper and

lower members of the valve and through the opening 36, 37. A retractile spring 42 tends to maintain the valve 38 in the closed position over the opening 36, 37, said spring 5 being connected at one end as at 43 to the valve and secured at its opposite end as at 44 to any fixed part of the generator 14. The valve 38 is normally maintained in the open position against the tension of the 10 spring 42 through the medium of the float 45 in the main water chamber 25, said float preferably being of box-like form having lugs 46 at the opposite sides slidably engaging vertical guide rods 47 in the chamber 25. The float 45 has secured thereto as at 49 one end of a pull string 48 which runs over a suitable guide 48^a and to connection as at 50 with the valve 38 below the partition 40. A vertical partition 14^a separates 15 the gas chamber 24 from the water chambers and in said vertical partition is an inlet opening 51 to permit water to flow from the water chamber 25 to the gas chamber 24. The opening is controlled by a valve 52, 20 here shown as a flat hinge valve.

With the described arrangement when the generator 14 is submerged as when the wearer of the belt is in the water, water entering the chamber 26 will pass downwardly 30 through the opening 36, 37, to the chamber 25 and rise in the latter sufficiently to cause the float 45 to rise, thereby relieving the pull string 48 of the weight of said float and permitting the spring 42 to swing the valve 38 35 to the closed position, thereby limiting the amount of water entering the chamber 25. The opening 51 leading to the gas chamber 24 is of limited capacity compared with the opening 35, 36, 37, it being the purpose to 40 cause the valve 38 to be closed when water in the gas chamber 24 has reached the soluble disk 32, the parts being so arranged that the float 45 will permit the spring 42 to close the valve 38 at the proper time, so 45 that said valve 38 will be closed in any event, even should the disk 32 be slow in dissolving. Ordinarily, however, the said disk will be dissolved permitting the water to reach the cartridge 28 for generating the gas, so 50 that the gas pressure will close the valve 52 and usually will force some water out through the opening 51 before the valve 52 closes. Obviously, gas generated in the chamber 24 will pass through the connection 55 13 to the belt 10 and cause the bags or sacks 12 to be inflated. It will be understood that the proportions of the parts are such that the total weight of the generator 14 will be markedly inferior to the buoyancy of the 60 inflated belt and gas sacks.

In the form shown in Fig. 5, is a slight variation of the valve, there being indicated in this figure a slide valve 38^a movable in a keeper 38^b over an opening 36^a of general

key-hold form, having a straight slot 37^a, 65 the closing spring 42^a being adapted to exert a straight pull on the valve.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims. 75

Having thus described my invention, I claim as new, and desire to secure by Letters Patent:

1. In a life-saving appliance of the class described, a box-like generator having a gas 80 chamber, material in said chamber adapted, when subjected to water, to generate gas, a water chamber, and a valve normally open and subject to gas pressure in the gas chamber to cut off communication between the 85 water chamber and gas chamber.

2. In an appliance of the class described, a gas generator including a gas chamber, a main water chamber, having an outlet leading to the gas chamber, an auxiliary water 90 chamber above said main water chamber and formed with an inlet for water when the generator is submerged, the top of said main chamber having an inlet opening leading from the auxiliary chamber, a valve controlling the last-mentioned controlling inlet opening, said valve comprising plates disposed respectively above and below the top of the main water chamber, a retractile spring in the auxiliary chamber and connected with the upper plate of the valve to close the latter, a float in the main water chamber, and connections between the float and the lower plate of the valve to maintain the valve open by the weight of the 105 float in the absence of water in the main chamber. 95

3. In an appliance of the class described, a gas generator having a gas chamber formed with an inlet for water, and a 110 holder in said chamber adapted to receive a cartridge of a character to generate gas when subjected to the action of water, said holder including a disk soluble in water and constituting a closure of the holder and cutting off communication between the interior of the holder and the gas chamber, and means to hold said disk in position. 115

4. In an appliance of the class described, a gas generator including a gas chamber 120 having an inlet for water, a holder detachably supported in said chamber, spring retainers yieldable to permit the entrance of a gas-generating cartridge into the holder, and a closure disk for the holder, said disk 125 being soluble in water.

5. In a life-saving appliance of the class described, a box-like generator having a

gas chamber, a holder contained within the gas chamber and adapted to hold material, the material which in the presence of water will generate gas, said holder being normally closed against the entrance of water thereto, means to admit water to the holder upon a rise of water to a predetermined

level in the gas chamber, a water chamber, and a valve subject to gas pressure in the gas chamber and controlling communication between the water chamber and gas chamber.

PAUL BERGEN.
